(57) **CLAIM**

The ornamental design for a machine for cleaning floors, as
shown and described.

DESCRIPTION

FIG. 1 is a front, top and left side perspective view of a
machine for cleaning floors showing the new design;
FIG. 2 is a front, top and right side perspective view thereof;
FIG. 3 is a front elevational view thereof;
FIG. 4 is a left side elevational view thereof;
FIG. 5 is a rear elevational view thereof;
FIG. 6 is a right side elevational view thereof; and,
FIG. 7 is a top plan view thereof.

The broken lines shown in the figures are included for
purposes of illustrating portions of the machine for cleaning
floors and form no part of the claimed design.

1 Claim, 7 Drawing Sheets
